GUN WHICH FIRES DURING FORWARD MOVEMENT OF THE GUN

Walter Ernesti, Berlin, and Heinrich Herlach, Berlin-Frohnau, Germany, assignors to Rheinmetall-Borsig Aktiengesellschaft, Dusseldorf, Germany, a corporation of Germany

Application May 18, 1938, Serial No. 208,682
In Germany August 20, 1936

5 Claims. (Cl. 89—27)

In order to reduce the recoil force of guns mounted on gun mountings and carriages, particularly in the case of guns of large calibre, it has been found to be advantageous for the gun

5 to be mounted so as to be capable of moving longitudinally as a whole on the mounting or carriage, and for the gun to be fired during its forward or running out movement. The gun may be arranged so as to slide directly or indirectly 10 on the cradle. In the latter case the gun rests on a sliding member which in its turn runs backwards and forwards in the cradle. In this case the movements of the sliding member are controlled by a running out spring and a recoil buffer 15 fitted in the cradle.

Such machine guns which are fired during the running out movement have a firing cam on the cradle and, on the slide, a firing mechanism which comes into contact therewith and 20 which, during the forward movement of the sliding member, by striking against the firing cam is brought into operation and actuates the trigger of the gun. The firing mechanism is returned to its original position by means of a spring. A 25 second spring makes the mechanism itself flexible, so that when the safety catch of the gun is in operation and the gun trigger is thereby held securely, it is not damaged by the action of the cam on the gun carriage.

30 As compared with this known form of construction, the invention provides an arrangement which, owing to the absence of several hitherto necessary structural members, makes firing during the running out movement considerably simpler to effect. A further advantage is the widened sphere of application, inasmuch as the firing of different kinds of ammunition which, owing to varying recoil forces cause a difference in the length of the running out path of the 35 gun, has no influence on the mode of operation of the firing device. Hitherto, when a change was made in the kind of ammunition it was also necessary to adjust the firing cam on the cradle.

According to the invention a firing lever is arranged bodily movable against the action of a resilient loading member, for example a spring, in the direction in which it is moved to effect firing by the cam plate on the gun carriage. The 40 spring or like member at the same time serves 45 to hold the lever or its bearing in the position of rest. In a further feature of the invention the lever is caused to bear, under spring influence, against its support (the gun or gun carriage slide) by means of adjustable abutments.

50 These lever abutments render it possible to

alter the extent of idle movement of the firing lever towards the gun trigger, and thus to effect a fine adjustment of the moment of firing. Moreover, by the adjustment of the abutments it is also possible to change the preloading of the 5 spring or its equivalent which holds the lever and its bearing in the normal position.

When, the safety catch having been released, the gun runs out for firing a shot, the firing lever is swung in its bearing by co-operation with the 10 fixed cam plate on the gun carriage, and actuates the gun trigger. The pivot bearing itself of the lever is thereby moved slightly. If, however, the safety catch is in operation and the trigger mechanism is secured the pivot bearing 15 is displaced to a greater extent, and when the gun runs out the firing lever, while swinging about its point of contact with the gun trigger (or firing pin) moves sufficiently to avoid damage to the cam members. Thus, the said resilient 20 mounting of the lever fulfils a double function. In the first place the firing lever is held firmly in its position of rest or after it has been actuated returns it to the position of rest, and in the 25 second place the firing device is protected from being damaged should the safety catch be in operation while the gun is running out.

An advantageous further development of the invention is the insertion of a pivotal arm between the firing lever and the controlling abutment on the gun carriage. Such a pivotal arm is held in a normal position under the influence of a helical spring and by an abutment which extends transversely to the running out direction. The arm retains its normal position when it 30 passes over the abutment on the gun carriage. During recoil, however, the arm is oscillated so that the firing lever is not actuated during the recoil movement.

If the type of ammunition is changed, for example, if instead of service ammunition, blank cartridges are used, in which case the running-out distance of the gun is shortened, it may occur that the pivotal arm does not pass over the abutment on the gun carriage but comes to a stop 45 against it with the firing lever in its displaced position. But because the gun, at the end of its backward movement has already compressed a buffer spring, it now moves flexibly backward for a little distance together with the firing lever. The pivotal arm pressed against the abutment in the gun carriage does not join in this movement, but is swung round and thereby renders it possible for the firing lever to swing into the 50 position of rest before a subsequent movement of 55

the gun. Thus the form of construction of the firing lever with a special pivotal arm, when one changes over from one kind of ammunition to another, ensures, without any loss of time in adjusting the cam, that the gun trigger shall be actuated only while the gun is running out.

An example of construction of a firing lever according to the invention is shown in the accompanying drawings in which—

10 Fig. 1 shows in a section through the gun the arrangement of the firing lever on the slide.

Fig. 2 is a side view of the lever and the cam on the gun carriage.

15 Fig. 3 is a section along the line III—III of Fig. 2.

Figs. 4 and 5 show the same section as Fig. 3 with the firing lever in a different position in each case.

20 Fig. 6 is a side elevation of the new gun on its carriage.

Fig. 7 is a horizontal section along line VII—VII of Fig. 6.

25 As shown in Fig. 6 the cradle *a* is provided with a latch plate *a*₁ to which is attached a tension wire *a*₂ which leads to a pedal *a*₃. On the slide *b* is a projection *b*₀ engaging the latch plate *a*₁ for the purpose of holding the slide as well as the gun in rearmost cocked or firing position.

30 Fig. 7 shows the inner construction of the gun. In the breech closure *c*₂ is arranged a longitudinally movable firing bolt *c*₃, which, during the recoil of the breech closure is brought into a rearward cocked position by the cocking lever *c*₄ against the action of the firing spring *c*₅, and 35 retained in said rearmost position by the sliding piece (sear) *c*₆. When the breech closure has again run forward, and the gun is ready for firing after closing, then the pressure lever *c*₇ stands opposite the sliding piece *c*₆. The projectile may 40 also be fired by pressing on the trigger pin *m* through the intermediary of the series of levers *m*₁, *m*₂ and *c*₇. In addition there is further arranged a safety device *m*₃ which with its nose *m*₄ can be brought manually, into engagement with the lever *m*₂ in order to prevent any unintentional 45 firing or release of the projectile.

50 The cradle *a* (Fig. 1) slidably carries the slide *b*, in which the gun *c* is fixed at the front by the trunnions *c*₁ and at the rear by means of a bolt not shown in the drawings. In a boring *b*₁ in the slide *b* is housed a compression spring *d* which bears at opposite ends against a flange *e*₁ of a bush *e*, and against a nut *f*₁. A spring bolt *f*₂ and a pivot *g* held in a bore in a flattened end *f*₃ (Fig. 2) of the bolt *f*₂ is drawn towards the gun. 55 The force on the bolt *f*₂ is transmitted by the pivot *g* to the firing lever *h* (which is adapted to oscillate about the pivot *g* between guide cheeks *b*₃ on the slide *b*) and, as long as the lever is in the position of rest shown in Fig. 1, is taken up by two abutment screws *i*₁ and *i*₂. The ends of these screws bear against the surface *b*₂ of the slide *b*.

60 The firing lever *h* is provided at the bottom with a roller arm *h*₂ which carries a roller *h*₃.

65 In the lower part of the lever *h* is a recess *h*₅ which is covered by a cover plate *h*₄ and contains a helical spring *h*₆ which holds the roller arm in its position of rest in which it bears against an abutment *h*₇ of the lever *h*. On the cradle *a* there is fixed by means of a bracket *k* a cam plate *l* which has guide surfaces *l*₁, *l*₂ and *l*₃.

The mode of operation of the firing device is as follows: When the slide *b* runs forward in the direction of the arrow in Fig. 3 the roller *h*₃ runs on the surface *l*₁ and *l*₂ (Figs. 3 and 4). Thus the lower part of the firing lever *h* is swung outwards from the gun and at the same time its upper end *h*₈ moves inwards and consequently the trigger pin *m* is pressed into the trunnions *c*₁. The pivotal point of the lever *h* is in this case the point of contact *n* of the abutment screw *i*₁ with the surface *b*₂. The abutment screw *i*₂ is raised in the movement of the cam *l* from the surface *b*₂ and the pivot *g* is drawn outwards somewhat against the influence of the spring *d*. If firing of the gun *c* is prevented by means of a safety catch, the trigger pin *m* cannot be moved and consequently the end *h*₈ of the lever cannot be swung inwards. In this case the point of contact of the cam plate *l* with the trigger pin *m* forms the pivotal point of the lever *h*, the abutment screws *i*₁ and *i*₂ are then both lifted from the surface *b*₂ and the bolt *g* is drawn outwards to a relatively great extent. On the further forward movement of the slide *b*, the roller *h*₃ runs from the guide surface *l*₂ over the surface *l*₃ inwards again, so that under the influence of the spring *d*, the lever *h* can return to its position of rest. During the recoil movement of the slide *b*, the roller *h*₃ is held back for a short time by the surface *l*₃, so that the roller arm *h*₂ oscillates with respect to the cam plate lever *l* into the position shown in Fig. 5. In this case the firing lever *h* itself remains in its position of rest. After the roller *h*₃ has run back over the cam *l*, the spring *h*₆ again causes the roller arm *h*₂ to bear against the abutment *h*₇.

Having now particularly described and ascertained the nature of our said invention and in what manner the same is to be performed, we declare that what we claim is:

1. A gun comprising a cradle having a cam, a 40 slide member in which the barrel of the gun is mounted and which is slidably mounted on the cradle, a trigger pin, a firing lever on the slide member associated with the trigger pin and operable by the cam upon the forward movement 45 of the slide member, and a pivotal mounting for the firing lever on the slide including a spring, said spring being adapted to permit the firing lever to be moved laterally together with its pivot when the trigger pin is locked against operation. 50

2. A gun according to claim 1, in which the firing lever is provided with abutment screws on its pivotal connection with the slide member with which the firing lever contacts the slide member. 55

3. A gun according to claim 1, in which the firing lever is provided with adjustable abutment screws on its pivotal connection with the slide member with which the firing lever contacts the slide member. 60

4. A gun according to claim 1, in which an oscillatable spring-urged arm is provided on the firing lever and operable by the cam.

5. A gun according to claim 1, in which the pivotal mounting includes a bolt having a flat-tened end and the firing lever is pivotally connected with a slot into which the bolt projects, said spring surrounding the bolt. 65
